Attorneys.

UNITED STATES PATENT OFFICE.

JOHN HART WILSON, OF BURKBURNETT, TEXAS.

DEVICE FOR CONNECTING PULL RODS TO WRIST PINS.

1,412,548.

Specification of Letters Patent. Patented Apr. 11, 1922.

Application filed January 18, 1922. Serial No. 530,148.

To all whom it may concern:

Be it known that I, JOHN H. WILSON, a citizen of the United States, and residing at Burkburnett, Wichita County, State of Texas, have invented certain new and useful Improvements in Devices for Connecting Pull Rods to Wrist Pins, of which the following is a specification.

The present invention relates to devices 10 for connecting the ends of pull rods of oil well pumps to the crank or wrist pin of a driving engine or power unit.

In a well known arrangement of pumps in the oil fields it is frequently desirable to 15 employ a single power unit, such as internal combustion engine, to furnish power necessary to operate pumping machines positioned at several different wells which are close to each other. Usually this power unit 20 or engine is connected, at the mouth of one well, directly to a pump positioned to lift the oil at that well and is connected by chains, ropes or "pull rods" with one or more pumps positioned at adjacent wells so 25 that these several pumps are simultaneously operated without necessitating the provision of a power unit for each individual well.

Generally the power unit has been provided with a crank which rotates in a vertical plane to which crank have been secured in various ways the pull rods or other linking devices connected to the adjacent pumps. The present invention has particular reference to means for detachably connecting the ends of the pull rods to the crank of the power unit and its object is to provide, as an article of manufacture, a device which may be readily secured to a wrist pin of the engine crank and to which in turn 40 may be readily attached the ends of the pull rods, the method of attachment being such that these rods may be readily disconnected. The device is light in weight though amply strong and is preferably a one-piece casting 45 which may be fabricated at low cost and yet which has the qualities necessarily possessed by such an article to accomplish its function in a satisfactory manner.

The invention may be embodied in various 50 forms one of which is disclosed in the following description when taken in connection with the accompanying drawings in which:

Figure 1 is a plan view of the device positioned on a wrist pin and having two pull rods connected thereto;

Figure 2 is an enlarged plan view of the device;

Figure 3 is a side plan view of the device; and

Figure 4 is a section on line 4—4 of Figure 3.

The shaft of an engine or power device is indicated at 10, a crank secured thereto at 11, and a wrist pin secured to the end of 60 the crank at 12. Pull rods are indicated at 13, 13, to the ends of which are secured hooks or catches 14, 14, which in turn are detachably secured to the member B which is mounted for rotation on the wrist pin 12. 65

The member B has a hollow cylindrical portion 15 which is lined with babbitt 16 or other antifriction metal. The wrist pin 12 of course extends through and fits within this babbitt lining. Extending radially and 70 in diametrically opposite directions from the central cylindrical portion 15 of member B are two arms or webs 17, 17, these webs terminating in disk-like portions 18 which have circular apertures 19 for the reception of 75 the hooked ends of the catches 14, or for the reception of similar hooks or catches. It will be seen that the apertures 19 are not concentric with the outer peripheries of the circular end portions 18. The thickness of 80 metal between apertures 19, 19 and the ends of member B is greater than the thickness of metal between the apertures and the edges (Figure 2), this extra metal being provided to compensate for the wear which occurs in the operation of the device due to the action of the catches 14. The ends 85 of the cylindrical portion 15 extend beyond the edges of webs 17 and serve as spacing rings to prevent contact between the crank 90 11 and the portions 18 of the webs, as the shaft and crank rotate.

As the crank 12 travels in a circular path and as there is some resistance to this movement exerted at right angles to the pull rods, 100 some lateral force will be exerted on the device which will tend to flex the same and to break off the webs 17 from the portion 15. To strengthen the device laterally transverse ribs or flanges 20 are provided at both 105 edges of the webs, these flanges serving to brace the webs from the cylinder 15. These transverse flanges are designed to provide an ample margin of strength against laterally exerted forces.

Preferably the device just described is 110 fabricated of cast steel which provides a

maximum strength for a given weight of metal and a given cost. Other materials may be used, if desired, and the device may be lined or unlined with babbitt as thought best. It is possible to provide a device of this character with more than two arms or webs 17 so that instead of two pumps a greater number of such pumps may be operated from a single power unit. In such cases 10 the crank pin is vertically disposed and the crank rotates in a horizontal plane. Other modifications may be devised without departing from the spirit of the invention.

Having thus described my invention what 15 I claim as new and desire to secure by Letters Patent is:

1. A device for connecting pull rods to wrist pins comprising a one-piece metallic member having a hollow cylindrical portion to receive a wrist pin and arms extending outwardly from said cylindrical portion in diametrically opposite directions, the ends of said arms being provided with means to permit the attachment of pull rods thereto 20 and the cylindrical portion extending axially beyond the arms in both directions, for the purpose set forth.

2. A device for connecting pull rods to wrist pins comprising a one-piece metallic member having a cylindrical aperture to receive a wrist pin and arms extending outwardly from said cylindrical portion in diametrically opposite directions, the ends of said arms being provided with eyes or apertures to receive the hooked ends of pull rod 30 securing devices, said eyes having thickened portions on the side remote from the cylindrical portion of the device, for the purpose set forth.

3. A device for connecting pull rods to 40 wrist pins comprising a one-piece metallic member having a cylindrical aperture to receive a wrist pin and radially extending arms provided with eyes to receive pull rod hooks or other fastening devices, and strengthening 45 flanges disposed at right angles to the axis of the cylindrical opening and integral with said cylindrical portion and said arms, for strengthening the arms against laterally exerted forces.

In testimony whereof I hereunto affix my signature.

JOHN HART WILSON.
